UNITED STATES PATENT OFFICE.

HARRIET RUTH TRACY, OF NEW BRIGHTON, NEW YORK.

SHUTTLE-ACTUATING MECHANISM FOR SEWING-MACHINES.

SPECIFICATION forming part of Letters Patent No. 471,037, dated March 15, 1892.

Application filed December 18, 1891. Serial No. 415,520. (No model.)

To all whom it may concern:

Be it known that I, HARRIET RUTH TRACY, a citizen of the United States, residing at New Brighton, in the county of Richmond and State 5 of New York, have invented certain new and useful Improvements in Shuttle - Actuating Mechanism for Sewing-Machines; and I do hereby declare the following to be a full, clear, and exact description of the invention, such 10 as will enable others skilled in the art to which it appertains to make and use the same.

This invention relates to sewing-machines.

The object of the invention is to produce a mechanism for imparting to the loop-taker of 15 a sewing-machine an intermittent movement, whereby a rotary motion will be imparted to the loop-taker to carry the loop of the needle-thread when presented to the loop-taker and to stop the same when a loop taken by the 20 loop-taker is being drawn up into the cloth, the cessation of movement being so timed as to allow the forward movement of the cloth and the operation of the feed during such cessation.

With these objects in view the invention 25 consists, essentially, in a sewing-machine comprising a driving-shaft provided with a gear-wheel, an independent shaft mounted adjacent to the main shaft and provided with a 30 gear-wheel meshing with that on the main shaft of the machine, a second gear-wheel loosely mounted on the independent shaft and gearing with the loop-taker of the machine, and two sliding pins, one mounted on the 35 frame of the machine and the other carried by a wheel interposed between the gear-wheels on the independent shaft and revolving with the shaft, and cams whereby the pins are alternately brought into contact with and drawn 40 from the loose gear-wheel.

In the accompanying drawings, forming a 45 part of this specification, and in which like letters of reference indicate corresponding parts, Figure 1 is an end elevation of a sewing-machine containing my invention. Fig. 2 is a side elevation of the shuttle and of the parts moving the same containing my invention. Fig. 3 is a detail view of a supporting device for the driving and stopping mechanism. Fig. 4 is a view in side elevation of a 50 wheel having a cam-groove, whereby the pins of the stopping mechanism are operated. Fig.

5 is a view, partly in section, showing the means for accomplishing the stopping and starting of the shuttle. Fig. 6 is a view similar to Fig. 3 with the pin-operating wheel in position, with the inner pins engaged and the outer pins free; and Fig. 7 is a similar view with the outer pins engaged and the inner pins free.

In the drawings, A represents the main driving-shaft of the machine, on which is placed a belt or other wheel, (not shown,) which receives motion from any suitable source, such as a treadle, motor, or the like. Motion from 65 the driving-shaft is communicated to the needle-bar and to the shuttle in any suitable well-known way to cause two reciprocations of the needle-bar to each complete revolution of the loop-taker.

One way of driving the loop-taker is shown 70 in the accompanying drawings. A large gear-wheel B, of suitable size and fixed upon the driving-shaft back of the loop-taker, has at each side of it and supported in hangers b on 75 shafts b² gear-wheels B² of one-half the diameter of the gear-wheel B, and meshing with this wheel, while mounted loosely on the outer ends of the shafts b², are gear-wheels B³ of the same diameter as the loop-taker. Interposed 80 between each of the gear-wheels B² and a gear-wheel B³ is the mechanism whereby the gear-wheels B³ are given motion from the shafts b² and are stopped twice during each revolution 85 of the shaft. This mechanism comprises a wheel C, fixed upon the shaft b² and carrying on its inner face a rigid pin, upon which slides a plate c², carrying a pin c³, which is capable 90 of sliding through a hole in the wheel C to project from the front face thereof or to be withdrawn to a position bringing its ends 95 flush with the outer face of the wheel. The upper portion of the plate c² projects a short distance above the pin c³, and this projection enters grooves d in plates D on the hangers as 100 the wheel C revolves. The grooves d are so formed that the pins c³ are moved into one of the curved slots d³ of the gear-wheel B³ at the time when the needle of the machine, through suitable intermediate mechanism, is at a position to present the loop of the needle-thread carried thereby to one of the hooks of the loop-taker. The pins c³, entering the slots d³,

turn the wheel B³ around half a revolution,

when the pins are withdrawn by grooves similar to the grooves d and pass through an open space between the plates D before they are again brought into engagement with the gear-wheels B^3 . The peripheries of the wheels C are provided with cam-grooves c^4 , in which rest plates c^5 , carrying pins c^6 . The plates c^5 are supported on the pins c^7 , which are placed in such position on the hangers b as to be opposite to slots b^4 in the gear-wheels B^3 . The pins receive a reciprocating motion during the operation of the machine, and the wheels C are so placed on their shafts that the pins c^6 are projected into one of the slots b^4 at the time when the pins c^8 are withdrawn from the slot b^3 , serving to check the motion of the gear-wheels.

As additional means of checking the motion of the gear-wheels B^3 , I provide the sprung-seated pins c^8 , with their outer ends rounded, these pins being designed to enter indentations in the inner face of the gear-wheels, placed in such position as to be opposite the pins c^8 when the impelling-pins are withdrawn.

The loop-taker of the machine is designated by the letter E . It is preferably made in the form illustrated in the drawings, decreasing in thickness from a point near its center toward its circumference, where the thickness

is so reduced as to present a small edge, and the periphery is provided with gear-teeth meshing with those of the gear-wheels B^3 .

Having thus fully described my invention, what I claim, and desire to secure by Letters Patent, is—

A sewing-machine comprising a loop-taker having peripheral engaging-gear and a driving-shaft provided with a gear-wheel, an independent shaft mounted adjacent to the main shaft and provided with a gear-wheel meshing with that on the main shaft of the machine, a second slotted gear-wheel loosely mounted on the independent shaft and gearing with the loop-taker of the machine, and two sliding pins, one mounted on the frame of the machine and the other carried by a wheel interposed between the gear-wheels on the independent shaft and revolving with the shaft, and cams whereby the pins are alternately brought into contact with and drawn from the loose gear-wheel, substantially as described.

In testimony whereof I affix my signature in presence of two witnesses.

HARRIET RUTH TRACY.
